(57) **CLAIM**

The ornamental design for a vertical channel base for multiple attachments, as shown and described.

DESCRIPTION

FIG. 1 is a top-front perspective view of a vertical channel base for multiple attachments showing my new design; FIG. 2 is a bottom-rear perspective view thereof; FIG. 3 is a left elevational view thereof; FIG. 4 is a right elevational view thereof; FIG. 5 is a top plan view thereof; FIG. 6 is a bottom plan view thereof; FIG. 7 is an enlarged front elevational view thereof; FIG. 8 is an enlarged rear elevational view thereof; FIG. 9 is a reduced top-front perspective view thereof showing a first exemplary attachment attached to the vertical channel base; and, FIG. 10 is a reduced top-front perspective view thereof showing a second exemplary attachment attached to the vertical channel base. The broken line showing exemplary attachments in FIGS. 9 and 10 is included for the purpose of illustrating environmental structure and forms no part of the claimed design.

1 Claim, 10 Drawing Sheets
